(57) **CLAIM**

The ornamental design for a trailer, as shown and described.

DESCRIPTION

FIG. 1 is a perspective view of a trailer, showing our new design.

FIG. 2 is a top view of the trailer of FIG. 1.

FIG. 3 is a right side view of the trailer of FIG. 1. The left side view is a mirror image of the right side view.

FIG. 4 is a front view of the trailer of FIG. 1; and, FIG. 5 is a rear view of the trailer of FIG. 1.

Any broken line portions of FIGS. 1–5 are included to show unclaimed subject matter only and form no part of the claimed design.

1 Claim, 4 Drawing Sheets(56)
